UNITED STATES PATENT OFFICE.

HARRY N. FOWLER, OF CHICAGO, ILLINOIS, ASSIGNOR TO M. C. FOWLER, OF CHICAGO,
ILLINOIS.

LAMP.

No. 914,259.

Specification of Letters Patent.

Patented March 2, 1909.

Application filed August 7, 1908. Serial No. 447,445.

To all whom it may concern:

Be it known that I, HARRY N. FOWLER, a citizen of the United States, and a resident of Chicago, in the county of Cook, in the 5 State of Illinois, have invented certain new and useful Improvements in Lamps; and I do hereby declare that the following description of my said invention, taken in connection with the accompanying sheet of 10 drawings, forms a full, clear, and exact specification, which will enable others skilled in the art to which it appertains to make and use the same.

This invention has general reference to 15 improvements in match lighters for automobiles, carriages, hearses, locomotive headlights, boat lights, pilot lights of stoves, furnaces, heaters, &c., and it consists, essentially, in the novel and peculiar combination 20 of parts and details of construction as hereinafter first fully set forth and described and then pointed out in the claims.

In the drawings already mentioned, which 25 serve to illustrate this invention more fully, Figure 1 is a side-elevation, and Fig. 2 a front-elevation of an automobile lamp and similar object embodying my invention, and being one of the various articles to which my invention is applicable. Fig. 3 is a longitudinal sectional plan of the match lighter 30 detached, said figure being taken in line $\alpha\alpha$ of Fig. 4. Fig. 4 is an end view of the same, and Fig. 5 a plan. Fig. 6 is a similar view of a fragment of the device showing a 35 slight modification of this device. Fig. 7 is a plan of the blank from which the outer tube of this device is made.

Like parts are designated by corresponding symbols and characters in all the various 40 figures.

The object of this invention is the production of a simple, efficient, durable, and cheaply-constructed match lighter for use in almost all instances where a light is to be 45 lighted, and especially so when exposed to the air, or in such places where ready access cannot be had to the place where a light or fire is to be ignited. For instance, in lighting automobile, carriage and other lamps, 50 when in the open air it is very difficult to light a match and ignite the lamp, owing to the wind extinguishing the match or the light before the lamp can be closed. Again, in stoves, furnaces &c., where usually a pilot 55 light is lighted to start the fire, these pilot

lights are difficult of access, being usually in out-of-the-way places. To provide for ready means for lighting such lights instantly and with positive certainty, I provide such lamps, pilot lights &c., with my invention 60 which consists, essentially, of a metallic open-seam tube 2, which tube forms the outer casing and has at its forward end a series of inwardly-bent prongs 3, and near its rear end a bead 4, said tube being securely 65 fastened to the lamp-body A or other object where a light is to be made, in such a manner that the forward end having the prongs 3 is in close proximity to the burner 5, and at a suitable angle thereto so as to insure positive 70 ignition. In the interior of this outer casing 2 there is, slidably arranged, another, smaller, open seamed, tube 6, the diameter and bore 7 of which is such as to retain a match 75 8, shown in dotted lines in Fig. 3, by frictional contact, said inner tube being made with an open seam and slightly less in diameter than the diameter of said match, so that the match must be forced into the open end of said inner tube 6 and is then held therein 80 by the clamping action of the open tube. In the outer end of the inner tube 6 there is provided a plug 9, to close this end, and this plug is supplied with a knob or button 10, wherewith the inner tube may be conveniently manipulated.

In order to retain the inner tube within the outer casing, the plug 9 is fitted with a projection or projections 11, engaging the outer casing 2 at the beaded part 4, and 90 thereby forming a snap-catch, owing to the fact that the outer casing, having an open seam, permits of expansion of the tube so that the projections 11 may pass into the same and, when reaching the groove 12, Fig. 95 3, engage therewith when the outer casing contracts to its normal size. Instead of this catch-mechanism as described, I may substitute a bayonet lock, 13, as shown in Fig. 100 6, or any other improved means for locking the inner tube to the outer casing.

The outer casing 2 is formed from a blank shown in detail in Fig. 7, it being a rectangular sheet of metal having on one end a series of tapering notches 14, and on opposite 105 edges tapering cut-outs 15, whereby the prongs 3 already referred to are produced. On the opposite end, this blank has an L-shaped slot 16, forming in conjunction with the projection 11 on the inner tube the lock 110

13 already mentioned. This blank is made from stiff sheet metal and rolled into tubular form in a manner readily understood by persons skilled in the arts to which this 5 method of sheet-metal working appertains.

In the ordinary matches most commonly in use, in which the lighting composition, (usually phosphorus,) is ignited by friction, the match is lighted when pushed out of the 10 outer casing and passing the sharp prongs 3. When, however, the so-called safety-matches are being used, which matches require to be rubbed over a prepared surface, such matches would not ignite by friction 15 alone, and in order to render their use possible, I provide the inner surface of the outer casing at the forked end with a prepared sheet of such igniting composition, which sheet is retained in position by the prongs 3, 20 and which may be removed from said tube, and replaced therein through the open outer end of said outer casing 2. This prepared surface is preferable formed into a tube and it may be cemented into the inner end of the 25 outer casing, if so desired.

It will now be readily observed that the inner tube, telescoping into the outer casing, can be readily unlocked from the outer casing and withdrawn therefrom, a match inserted into the open end of the inner tube and the latter returned into the outer casing where the head of the match, coming in contact with the prongs is ignited and pushed out of the outer casing into close proximity 30 to the burner to be lighted. The intense heat generated by the match at the moment of its ignition, will invariably light the burner even when the heaviest kind of fuel or candles are used, and as in the case of 35 lamps, this is accomplished without opening the door of the lamp, and in the strongest wind in the open air. The unconsumed portion of the match remaining in the inner tube can be easily pulled out of the same, 40 but if too short to be clasped or grasped, it may be readily removed by inserting a knife-blade or other thin object into the open seam of the said inner tube, or a thin sheet-metal strip may be removably affixed to the 45 inner tube, or a suitable ejector provided therein, if desired, and in Fig. 5 I have shown such an ejector affixed to the button 50 10, said ejector consisting of a thin strip of metal 19, secured to the button 10 by a 55 chain 18.

The device heretofore described is composed of but a few parts which are readily manufactured in suitable dies, and which can be produced at a very low cost.

60 While I have heretofore described the preferred form in which my invention may be carried into effect, I do not wish to confine

myself to the precise details set forth, since these may be varied without departing from my invention. For instance, while I prefer 65 to make the outer casing from a blank formed into a tube having an open seam I may produce the same from a so-called open-seam tube, which is a regular and well-known article of manufacture. I may also produce 70 this tube from seamless, or brazed tubing and saw the same open to produce the desired effect of elasticity and expansibility. Such and other minor variations which produce 75 the desired results may be resorted to if desired.

Having thus fully described this invention I claim as new and desire to secure to me by Letters Patent of the United States—

1. In a lamp, the combination, with the 80 lamp-body, of a match lighter, consisting of an outer, open seam casing attached to said lamp-body, and projecting inwardly into the same and terminating in proximity to the burner, said outer casing being provided with 85 inwardly-projecting prongs at one end and having an internal groove near its other end; an open seamed inner tube slidably arranged in said outer casing and having a plug and button at one end, and a locking device for 90 removably securing said inner tube to the said outer casing.

2. As an improved article of manufacture, a match lighter adapted for use in connection with a lamp or similar object, said match 95 lighter consisting of an outer open seam casing, there being a series of inwardly-projecting prongs on the end of said outer casing; an inner tube having an open seam, said tube being slidably arranged within the outer casing, said tube having a bore adapted to hold a friction match in its end; a button on the end of said inner tube; a catch whereby said inner tube is removably secured to the outer casing, and an ejector for said match. 105

3. A match lighter consisting of an outer casing having an open seam; inwardly-projecting prongs on one end of said casing, and a bead on or near to the other end whereby an inner, annular, groove is afforded therein; 110 an inner open seam tube of a bore adapted to hold a friction match in its end; a plug at one end of said inner tube, and a button on said plug; an ejector plate, and a chain attached thereto and to the button; and a catch for 115 locking the inner tube to the outer casing.

In testimony that I claim the foregoing as my invention I have hereunto set my hand in the presence of two subscribing witnesses.

H. N. FOWLER.
